UNITED STATES PATENT OFFICE.

WILLIAM H. MCKENZIE, OF OAKLAND, CALIFORNIA.

CUTTING TOOL.

1,409,960.

Specification of Letters Patent. Patented Mar. 21, 1922.

Application filed June 10, 1920. Serial No. 387,897.

To all whom it may concern:

Be it known that I, WILLIAM H. MCKENZIE, citizen of the United States, residing at Oakland, in the county of Alameda 5 and State of California, have invented certain new and useful Improvements in Cutting Tools, of which the following is a specification.

This invention relates to an improved cutting tool and has as one of its principal objects to provide a device of this character wherein the tool will be so formed that a tool body of one grade of material may be employed while the tool bit only will be 15 formed of a hardened high grade material, thus effecting a pronounced saving in production cost.

The invention has as a further object to provide a tool which, while employing different grades of material for the tool body and bit respectively, will, nevertheless, operate with an efficiency equal to any ordinary cutting tool.

And the invention has as a still further 25 object to provide a tool wherein the tool bit will be firmly and securely mounted upon the tool body so that chattering or displacement of the bit will not occur.

Other and incidental objects will appear 30 hereinafter.

In the drawings:

Figure 1 is a fragmentary perspective view of my improved cutting tool.

Figure 2 is a transverse section taken on 35 the line 2-2 of Figure 1, and looking in the direction of the arrows.

Figure 3 is a fragmentary perspective showing the head of the tool body and the mounting of the bit thereon, the head of the 40 tool body being partly broken away and shown in section, and

Figure 4 is an elevation showing a slight modification of the invention.

In carrying the invention into effect, I 45 employ a tool body having a head 10 from which extends a somewhat reduced shank 11. At its outer end the head is formed with a rounded nose 12 while the upper side of the head at its outer end portion is cut away to 50 provide a flat face 13 sloping rearwardly from the outer end of the nose and inclining sharply toward one side of the head. Formed medially of the head is a longitudinally extending slot 14 opening through the 55 upper side of the head and through the outer end thereof. As particularly brought

out in Figure 2, this slot is substantially dove-tail in cross section and extending rearwardly from the inner end of the slot is, as best seen in Figure 3, a longitudinally directed socket 15 opening through the flat inner end wall of the slot.

Pressed into the slot 14 of the tool body is a bit 16. This bit is dove-tail in cross section to snugly fit within the slot and, at 60 its upper side, lies flush with the upper side face of the head 10. At its rear end the bit is formed with a flat wall to abut the flat inner end wall of the slot and extending rearwardly from the inner end of the bit is 65 a locking stud 17 therefor having binding engagement within the socket 15 of the head. As will thus be perceived, the sloping walls of the bit will coat with the sloping walls of the slot 14 to prevent any chattering of 70 the bit upon the head of the tool body while the locking stud 17 will serve to firmly secure the bit against forward displacement. At its outer end portion, the upper side of 75 the bit is cut away to provide a flat face lying flush with the flat face 13 of the head and the outer end of the bit is rounded to lie flush with the rounded face of the nose 12.

Attention is now directed to the fact that 80 by constructing the tool as just described, it is possible, without sacrificing any beneficial results, to form the tool body from a relatively cheap grade of material and employ a high grade material only in the bit. The tool body is preferably formed of cold 85 rolled steel while what is generally known as high speed tool steel is employed in forming the bit. As is well known, high speed tool steel is quite expensive and, as will thus be at once appreciated, I provide a tool 90 wherein a material saving is effected in production cost. Heretofore, it has been found difficult to properly secure a hardened bit upon a tool body of softer material since the hard metal of the bit would, in the practical 95 use of such a tool, soon stretch the tool body sufficiently to cause looseness of the bit. However, in the present instance, I have overcome these disadvantageous features by the provision of the locking stud 17 upon 100 the bit, this stud serving not only to counteract longitudinal canting of the bit but also acting to hold the bit against longitudinal outward displacement.

In Figure 4 of the drawings, I have illustrated a slight modification of the invention 110 wherein a tool body is employed having a

shank 18 at the forward of which is a laterally directed head 19. This head is identical with the head 10 of the preferred construction and carries a bit 20 like the bit 16. The distinguishing feature of the modified structure lies in the fact that the head of the tool body is directed laterally to provide a right hand tool. As will be seen, a left hand tool could be readily formed by directing the head of the tool body laterally in the opposite direction. I accordingly reserve the right to all such minor variations of the invention as may fall within the spirit of the appended claims.

15 Having thus described the invention, what is claimed as new is:

1. A cutting tool including a body having a head provided with a slot opening through the upper side of the head and through the outer end thereof, the slot being formed with converging walls, and a bit seated in said slot and engaged by said walls to be held

thereby against upward movement within the slot, the bit being provided with locking means extending rearwardly therefrom and coacting with the head for securing the bit against outward longitudinal displacement. 25

2. A cutting tool including a body having a head provided with a slot, there being a socket formed at the inner end of said slot, 30 and a bit seated in the slot and provided with locking means engaging in said socket for securing the bit against outward longitudinal displacement.

3. A cutting tool including a body having a head provided with a slot, there being a rearwardly directed socket extending from the inner end of said slot, and a bit seated in the slot and provided at its inner end with a rearwardly directed stud engaging in said 40 socket and securing the bit against outward longitudinal displacement.

In testimony whereof I affix my signature.
WILLIAM H. MCKENZIE. [L. S.]
